THREAD CONTROL MECHANISM

Frank A. Kucera, Chicago, Ill., assignor to Union Special Machine Company, Chicago, Ill., a corporation of Illinois

Application August 3, 1940, Serial No. 350,277

11 Claims. (Cl. 112—242)

This invention relates to thread control mechanism useful in connection with sewing or other textile machines where it is desired that a plurality of threads be released in a predetermined relative rate in accordance with the character of the work to be produced by the machines. More specifically, the invention has reference to thread control mechanism operative under the principle disclosed in a co-pending patent application Serial No. 348,373, filed July 30, 1940, by John F. Cahill, administrator for Albert S. Riviere, deceased, wherein individual threads en route to the instrumentalities by which they are manipulated, travel one or more times respectively about peripheral portions of a freely mounted wheel, said wheel being rotated as a consequence of the tangential pull induced in one of the threads by its manipulating instrumentality with the result that proportionate amounts of the other threads are tolled off for use by their respective manipulating instrumentalities. While the arrangement in the co-pending application referred to serves very satisfactorily in the performance of the function for which it is designed, it is to be noted that to re-thread the machine in the event that one or more of the threads are broken, some time is required since they pass about different peripheral portions of a single wheel.

According to my present invention as herein-after more fully set forth, I facilitate the threading operation by forming the thread control wheels as separate units, and by providing means whereby the wheels are connected for rotation in unison normally, with capacity for being detached however, so that they may be independently rotated for re-threading.

Other objects and attendant advantages will appear from the following description of the drawing, wherein.

Fig. 1 is a fragmentary view, in front elevation, of a sewing machine conveniently embodying the thread control mechanism of my invention.

Fig. 2 is an elevation of the thread control mechanism looking as indicated by the angled arrows II—II in Fig. 1, with the thread control wheels released for convenience of independent rotation.

Fig. 3 is a fragmentary sectional view taken as indicated by the angled arrows III—III in Fig. 1.

Fig. 4 is a detail sectional view taken as indicated by the arrows IV—IV in Fig. 3.

The machine herein illustrated for the purposes of exemplifying my invention is generally of the type disclosed in another copending patent appli-

cation Serial No. 219,611 filed by Charles F. Rubel on July 16, 1938, which has matured into Patent No. 2,254,875 Sept. 2, 1941. As shown, the machine has tangentially-opposed intermittently-rotating vertical axis feeding wheels or "cups" 10 and 11 which are relied upon to intermittently advance, between them, a plurality of superposed fabric edges for presentation to the stitch forming instrumentalities of the machine. These instrumentalities include a needle 12, a cooperating main looper 13 and an overedge looper 14, for manipulating individual threads N, L, and O in the formation of a joining seam through and around the fabric edges. The needle 12 is secured 10 to an endwise reciprocating horizontal shaft or bar 15, the main looper 13 to an oscillating shaft 16 which is inclined somewhat to the horizontal, and the overedge looper 14 to a similarly inclined shaft 17 which is reciprocated endwise as well as 15 oscillated about its axis. The shafts 15, 16 and 17 derive their movements in properly timed relation from suitable actuating mechanism concealed within the frame 18 of the machine. The needle thread N is subject to the action of a take up eye 19 adjustably fixed on the shaft 17 of the overedge looper 14, said eye engaging the thread in 20 the interval between a guide eye 20 on the needle bar 15 and a fixed eye 21 on the machine frame 18. The main looper thread L is similarly engaged by the take up eye 19 in the interval between the eye of the looper 13 and another fixed eye 22 on the machine frame; while a third fixed 25 directing eye 23 on the machine frame operates to keep the overedge looper thread O out of the way of the other two threads in its passage to the eye of the overedge looper 14.

The mechanism which I have devised for controlling the threads N, L and O en route from individual sources of supply (not illustrated) to the manipulating instrumentalities 12, 13 and 14 of the machine, is comprehensively designated in the drawings by the numeral 25. As shown in Fig. 1, this mechanism is located at the front of the laterally-projecting top portion 18a of the machine frame. From Fig. 3 it will be noted that the mechanism 25 comprises a shouldered anchorage nipple 26 whereof the threaded shank 27 engages into the machine frame. Axially threaded into the nipple 26 is a screw stud 28 the free end of which serves as an axle and which has a stop shoulder at 29 to engage the face of said nipple, together with a slotted head 30 at its outer end. Mounted with capacity for free rotation on the axle 28, is a tubular shaft or sleeve 31 having a circumferentially-grooved annular enlargement 35

32 at its inner end which serves as a control wheel and about which the needle thread N is wrapped one or more times as shown in Fig. 3. Freely mounted, in turn, upon the sleeve 31 are two peripherally-grooved wheels 33 and 34 which are of like diameter but larger than the wheel 32 and about which the looper threads L and O are respectively likewise wrapped one or more times, as shown in Fig. 3. It is to be noted from Fig. 2 that the wheels 32, 33 and 34 are respectively provided with edge notches 32a, 33a and 34a in one of their flanges for holding the ends of the respective threads N, L and O incident to initial winding. An annular recess 35 in the rear face of the wheel 32 is occupied by a collar 36 which is secured against rotation on the axle 28 by a key 37. As shown, the collar 36 has angular notches 38 (Fig. 4) in its periphery providing camming surfaces to coat with pins shown at 39 after the manner of a roller clutch in preventing rotation of the sleeve except in the direction of the arrows in Figs. 1 and 4. Surrounding the sleeve 31 in the interval between a nut 40 at the outer end thereof and the wheel 34 is a collar 41 with an outwardly-flaring frusto-conical grasp portion 42, said collar being notched as at 43 to engage a stud 45 on said sleeve. The helical spring shown at 46 in Fig. 3 yieldingly maintains the collar 41 in frictional pressure contact with the wheel 34 with the result that the latter in turn clamps the wheel 33 against the wheel 32. As a consequence of this construction, it will be seen that the three wheels 32-34 are normally coupled for rotation in unison about the stud 28. However, by drawing the collar 41 outward against the action of the spring 46 to clear the stud 45 and thereafter rotating it slightly to bring the slot 43 past the stud as shown in Fig. 2 to lock said collar in retracted position, the wheels 33 and 34 will be freed so that they may be rotated independently of the wheel 32 for a purpose presently explained. Secured between the contiguous faces of the machine frame 18 and the head of the nipple 26 is a thread guiding element 47 of angular configuration (Figs. 1 and 2), whereof the leg ends 48 and 49 are bent laterally and pierced at intervals for passage of the threads N, L and O through them.

Disposed on the machine frame 18 closely adjacent the thread control device 25 is a thread tensioning device 50 (Fig. 1) consisting of a fixed stud 51 and a plurality of spring-pressed tension disks 52 (whereof but one is visible) which are free to rotate on said stud, and between pairs of which the threads N, L and O reeve.

In traveling from their separate sources of supply, the threads N, L and O, first pass through the tension device 50, then through the eyes in the leg 48 of the guiding element 47, then around the wheels 32, 33 and 34, and then through the apertures in the other leg 49 of said element. From thence, the threads L, N, and O continue on their way to the needle 12 and the loopers 13 and 14, after having traversed the usual guides of the machine in the manner previously explained.

During the operation of the sewing machine, the wheels 32, 33 and 34 will be rotated in the direction of the arrow in Fig. 1 by tangential pull of one of the threads, and since said wheels are obliged to rotate together, definite amounts of the other two threads will be tolled off in proportion to the respective diameters of the corresponding wheels. In the event of breakage of any of the threads, the wheels 33 and 34 are released

by withdrawing the collar 41 in the manner already understood. With this accomplished, the wheels 32, 33 and 34 may be independently rotated to pay out sufficient of the broken threads for the re-threading of the machine, with minimum loss of time, whereupon the collar 43 is again released to reclamp the wheels 33 and 34 preparatory to resumption of the sewing. The arrangement, it will be noted, makes possible the positional interchange of the wheels or the substitution of wheels of different diameters in accordance with the requirements of special conditions which may be encountered in practice.

My invention is not to be regarded as limited to the precise number of thread control wheels herein illustrated by way of example, since this number may, within the scope of the appended claims, be varied in accordance with the requirements of the sewing machine with which the thread control mechanism is used.

Having thus described my invention, I claim:

1. Thread control mechanism for a textile machine with a group of cooperating thread concatenating instrumentalities, comprising a corresponding number of coaxial control wheels around which the threads for said cooperating instrumentalities are individually wrapped for travel thereabout en route to the respective concatenating instrumentalities; and means for connecting the wheels so that they are rotated in unison normally under the pull of one of the threads, said means being capable of releasing the wheels for independent rotation to facilitate threading.

2. Thread control mechanism for a textile machine with a group of cooperating thread concatenating instrumentalities, comprising a corresponding number of control wheels around which the threads are individually wrapped for travel thereabout en route to the respective concatenating instrumentalities, and means for connecting the wheels so that they are rotated in unison normally under the pull of one of the threads, said means being capable of releasing the wheels for independent rotation to facilitate threading of said instrumentalities, and means to prevent reverse rotation of the wheels.

3. Thread control mechanism for a textile machine with a group of cooperating thread concatenating instrumentalities, comprising a corresponding number of control wheels mounted side by side on a common axis, around which the threads are individually wrapped one or more times for travel thereabout enroute to the respective concatenating instrumentalities; and means for connecting the wheels so that they are rotated in unison normally under the pull of one of the threads, said means being capable of releasing the wheels for independent rotation to facilitate re-threading of said instrumentalities in the event of rupture of one or more of the threads.

4. Thread control mechanism for a textile machine with a group of cooperating thread concatenating instrumentalities, comprising a corresponding number of coaxial control wheels around which the threads are individually wrapped one or more times for travel thereabout en route to the respective concatenating instrumentalities; each wheel having a notch in its periphery to receive and hold the corresponding thread during initial winding of the latter on the wheel; and means for connecting the wheels so that they are rotated in unison normally under the pull of one of the threads, said means being capable of re-

leasing the wheels for independent rotation to facilitate re-threading of said instrumentalities in the event of rupture of one or more of the threads.

5. The combination with thread control mechanism according to claim 1, of means for imposing uniform tension upon the threads en route to the control wheels.

6. Thread control mechanism for a textile machine with a group of cooperating thread concatenating instrumentalities, comprising a freely rotatable shaft; a plurality of control wheels mounted side by side on the shaft and around which the individual threads are wrapped one or more times for travel thereabout en route to the respective concatenating instrumentalities; and means connecting the wheels to the shaft so that they are rotated in unison normally under the pull of one of the threads, said means being capable of releasing the wheels for independent rotation to facilitate re-threading of the machine in the event of rupture of one or more of the threads.

7. Thread control mechanism for a textile machine with a group of cooperating thread concatenating instrumentalities, comprising a freely rotatable shaft; a plurality of control wheels mounted side by side on the shaft and around which the individual threads are wrapped for travel thereabout en route to the respective concatenating instrumentalities; and means connecting the wheels to the shaft so that they are rotated in unison normally under the pull of one of the threads, said means being capable of releasing the wheels for independent rotation to facilitate re-threading of the machine in the

event of rupture of one or more of the threads and means to prevent reverse rotation of the shaft.

8. Thread control mechanism according to claim 6, wherein the shaft has a head which constitutes one of the control wheels; and wherein the connecting means includes an axially-slidable spring-pressed collar on the shaft between which collar and the head, the other control wheels are normally clamped against independent rotation.

15 9. Thread control mechanism according to claim 6, wherein the shaft is tubular and rotates on a fixed axle; and wherein the shaft is restrained against reverse rotation by clutch means which includes a plurality of circumferentially arranged rollers which are arranged to engage the internal surface of the shaft and which coat with angular cam notches in the surface of the axle.

20 10. Thread control mechanism according to claim 6, wherein the wheels are circumferentially grooved, and wherein each wheel has a notch in one of its circumferential flanges in which the thread may be engaged and temporarily held to facilitate initial winding of the thread in the groove.

25 11. The invention according to claim 7, in which one of the wheels is secured to the shaft and the others are rotatably mounted thereon; and in which the said means is spring influenced and maintains said other wheels in frictional engagement with each other and with the first mentioned wheel for restraint normally against independent rotation.
